UNITED STATES PATENT OFFICE.

JAMES C. SAFAR, OF SEATTLE, WASHINGTON.

DESIGN FOR A CASING FOR MASSAGE-VIBRATORS.

43,807.

Specification for Design.

Patented Apr. 1, 1913.

Application filed December 26, 1912. Serial No. 738,747. Term of patent 14 years.

To all whom it may concern:

Be it known that I, JAMES C. SAFAR, a citizen of the United States, and resident of the city of Seattle, in the county of King and State of Washington, have invented a new, original, and ornamental Design for Casings for Massage-Vibrators, of which the following is a specification, reference being had to the accompanying drawing, forming a part thereof.

The figure of the drawing is a perspective showing my new design.

What I claim is,

The ornamental design for a casing for massage vibrators, as shown.

J. C. SAFAR.
